UNITED STATES PATENT OFFICE.

JOHN MITCHELL AND JOHN CECIL GEORGE COSSEY, OF LONDON, ENGLAND.

CENTRAL BUFFER COUPLING FOR RAILWAY AND LIKE VEHICLES.

Application filed August 14, 1922, Serial No. 581,886, and in Great Britain December 20, 1921.

The invention relates to central buffer couplings for railway and like vehicles and consists in improvements by which the under frames are to a large extent relieved from the draw and buffer stresses.

For this purpose the draw and buffer springs are disposed centrally in the under frame and the stresses exerted on the coupler at one end of the vehicle are directly transmitted to the coupler at the other end of the vehicle.

The accompanying drawings illustrate examples of couplings according to the invention. Fig. 1 is a sectional plan of one construction and Fig. 2 a similar view of a slight modification.

In the arrangement shown in Fig. 1, the central longitudinals of the under frame are shown at A' and A². Two box shaped members B', B² are fitted between the under frames and their outward longitudinal movements are restricted by abutments a, a' formed on or attached to the under frames.

25 A drawbar C' passes through the inwardly disposed ends b', b² of the boxes B', B² and is guided and supported by bearings d', d² provided in these ends. The main draw and buffering springs E', E² are disposed between the ends b', b² of the boxes. An auxiliary spring F' surrounding the extended end of the drawbar C' is compressed between a boss g' on the box B² and a washer h' on the drawbar, the compression of the spring being adjusted by a nut i' screw threaded on the drawbar.

30 Bars J', J² are slidable in bearings provided in the ends b', b² of the boxes B', B² and pass through the springs E', E² and also 40 through lugs k', k² on a connecting bridge piece K; these bars are held, respectively, against the box B' and the bridge piece K by nuts j and j', which serve to adjust the pressure of the springs E', E².

45 A bar C², which with the bars J', J², forms the drawbar on the right of the vehicle, passes through an aperture provided in the bridge piece K, and an auxiliary spring F² is compressed between a boss g² of the bridge piece and a washer h² on the bar C², a nut i² on the end of the bar serving to adjust the pressure on the spring.

50 The auxiliary springs F', F² take up the initial draft stress. The further draft and the buffering stresses are taken up by the springs E', E².

Bearings M', M² provided in the outer ends of the boxes B', B² support the drawbars C', C² and vertical pins L', L² in the drawbars allow relative movement in the horizontal plane between these bars and the coupler heads.

55 On a draft pull exerted on the rod C¹ the box B² is moved to the left (viz, in the direction of the pull exerted) first compressing the comparatively light spring F¹ and then the stronger springs E¹, E². The box B¹ cannot move to the left because of the abutments a, a' on the left. The drawbar C¹ and the pin L¹ during the movement 70 slide in the bearing M¹. Under the action of a buffering stress the box B¹ is moved to the right, compressing the springs E¹, E², the box B² being prevented from moving in that direction by the abutments a, a'. If the 75 draft stress is applied in the right hand direction, the stress is transmitted by the rods J', J² to the box B' which is moved to the right.

80 In the arrangement shown in Fig. 1, the box B² in which the two auxiliary springs F', F² are contained is longer than the box B'.

The arrangement shown in Fig. 2 differs 85 from the preceding only in the disposition of the auxiliary springs F', F², by which the boxes B', B² are of the same length. The bars J', J² are extended beyond the inner end wall b' of the box B' and are secured to a bridge piece N adapted to slide on the 90 drawbar C'. The auxiliary spring F² is disposed between the bridge piece N and the end plate b' of the box B'. The action is substantially the same as described in connection with Fig. 1.

95 Central buffer couplers can be applied to vehicles in which the under frames have been designed for side buffers, since the under frames which are usually too weak to withstand the buffering stresses of a central 100 buffer coupling are according to the invention relieved from the greater part of these stresses.

Having thus described the nature of the 105 said invention and the best means we know of carrying the same into practical effect, we claim:—

110 1. A central buffer coupling for railway and like vehicles comprising in combination an under frame and longitudinals connected thereto, box members adapted to slide between said longitudinals, resilient means dis-

posed between the inner ends of said box members and taking up both draft and buffing stresses in either direction, a pair of drawbars each of which is connected to the 5 inner end of one box member and is adapted to slide in the end walls of the other box member.

2. A central buffer coupling for railway and like vehicles comprising in combination 10 an under frame and longitudinals connected thereto, box members adapted to slide between said longitudinals, abutments on said longitudinals limiting the outward movements of said box members, resilient means 15 disposed between the inner ends of said box members and taking up both draft and buffing stresses in either direction, a pair of drawbars each of which is connected to the inner end of one box member and is adapted 20 to slide in the end walls of the other box member.

3. A central buffer coupling for railway and like vehicles comprising in combination 25 an under frame and longitudinals connected thereto, box members adapted to slide between said longitudinals, resilient means disposed between the inner ends of said box members and taking up both draft and buffing stresses in either direction, a pair of drawbars each of which is connected to the inner end of one box member and is adapted 30 to slide in the end walls of the other box member, resilient means, adapted to take up the initial draft stresses, being interposed 35 between each drawbar and the box member to which it is connected.

4. A central buffer coupling for railway and like vehicles comprising in combination

an under frame and longitudinals connected thereto, box members adapted to slide between said longitudinals, abutments on said longitudinals limiting the outward movements of said box members, resilient means disposed between the inner ends of said box members and taking up both draft and buffing stresses in either direction, a pair of drawbars each of which is connected to the inner end of one box member and is adapted to slide in the end walls of the other box member, resilient means, adapted to take up 40 the initial draft stresses, being interposed 45 between each drawbar and the box member to which it is connected.

5. A central buffer coupling for railway and like vehicles comprising in combination 55 an under frame and longitudinals connected thereto, box members adapted to slide between said longitudinals, resilient means disposed between the inner ends of said box members and taking up both draft and buffing 60 stresses in either direction, an axially arranged drawbar connected to the inner end of one box member and adapted to slide in the end walls of the other of said box members, and an axially arranged drawbar 65 at the other end of said coupling, an extension of said drawbar, comprising a pair of parallel rods, adapted to slide in the inner end walls of said box members, and a bridge 70 piece connecting the outer ends of said parallel rods.

In testimony whereof we have signed our names to this specification.

JOHN MITCHELL.

JOHN CECIL GEORGE COSSEY.
